ELECTRIC IGNITION SYSTEM.

1,124,028.

Specification of Letters Patent.

Patented Jan. 5, 1915.

Application filed September 21, 1911. Serial No. 650,604.

To all whom it may concern:

Be it known that I, GOTTLÖB HONOLD, a subject of the Emperor of Germany, and residing at Stuttgart, Germany, have invented 5 certain new and useful Improvements in Electric Ignition Systems; and I do hereby declare the following to be a full, clear, and exact description of the invention, such as will enable others skilled in the art to which 10 it appertains to make and use the same.

This invention relates to an electric ignition system for internal combustion engines, and particularly to a system for starting and running, wherein a mechanical interrupter and a buzzer, but no battery, are employed, and wherein the necessary retardation 15 of the ignition period during starting and the desirable advancement of the spark during running are obtained without any 20 mechanical adjustment whatever.

The invention consists in connecting a buzzer with a switch in electrical parallel with a mechanical interrupter, and connecting both in series with the inducing winding of an ignition machine, so that by closing the switch for starting the engine, the current from the ignition machine flowing to the buzzer when the mechanical interrupter is open, is rapidly interrupted as a 25 result of the vibration of the buzzer armature, thereby producing a rapid succession of sparks at the spark plug, and such sparks necessarily occur later in the stroke of the engine than the period of actuation of the 30 interrupter due to the inductance of the buzzer winding. During the running operation of the engine, the buzzer is cut out of operation by opening the switch, and then single sparks are produced at the spark plug 35 by the currents from the ignition machine at advanced periods corresponding to the actuation of the interrupter. For this purpose, it is preferable, though not essential, to use a primary and secondary winding on 40 the armature of the ignition machine so as to increase the sparking potential.

It has been assumed heretofore, that the voltage generated by an ignition machine during the period of slow rotation in starting 45 is not sufficiently high to produce a spark capable of igniting the compressed combustible mixture in the engine cylinders. However, recent experiments have demonstrated that this observation is correct only 55 in a limited sense. By a suitable construc-

tion and arrangement of the ignition machine, sparks may be produced in the combustible mixture even during the starting period of the engine, but the energy of the spark is so slight that ignition is not certain 60 with a single spark. It is known also, that ignition may be secured with quite feeble sparks rapidly succeeding each other, instead of a single spark of feeble character, and that such a series of sparks can be obtained by means of a buzzer. Furthermore, 65 it is known that a buzzer may be connected to an ignition machine, but this combination has been employed only in such manner that the buzzer remained in the circuit during 70 the running period also, and therefore, by this arrangement the necessity of advancing the ignition period as the speed of the engine increased was always essential.

The present invention utilizes for the first 75 time the characteristic feature of a buzzer that the spark produced thereby is necessarily retarded, the effect of which is that the mechanical interrupter may be adjusted for advanced ignition for both the starting 80 and the running period of the engine. When the buzzer circuit is completed by closing the switch during the starting period of the engine, the spark is retarded sufficiently as a result of the inductance of the 85 buzzer winding in spite of the advanced adjustment of the interrupter. When the engine gets under way, the buzzer is cut out of operation by opening the switch, so that the desired advanced ignition during the running 90 period of the engine is automatically established in consequence of the advanced adjustment of the interrupter.

The accompanying drawing illustrating 95 my invention is a diagrammatic representation of the preferred arrangement.

The primary inducing winding *p* of the armature *a* of any suitable type of ignition machine is connected in electrical series with a switch or push button *b* and the buzzer 100 winding *c* and buzzer armature *f* in one parallel branch, and also in electrical series with the mechanical interrupter *d* in another parallel branch, the circuits being grounded as indicated. The primary winding *p* is 105 periodically short-circuited and opened in the well known manner by the mechanical interrupter *d* mounted upon the armature shaft. The secondary inducing winding *s* of the armature *a* is electrically connected 110

2
to the spark plug *e*. The ignition machine is operatively connected to the engine in the well known manner.

When the engine is to be started, the 5 switch *b* is closed, and as soon as the ignition machine begins to rotate, the winding *c* of the buzzer is excited by the current from the primary winding *p* so long as the mechanical interrupter *d* is open, thereby 10 vibrating the buzzer armature *f* and producing a rapid succession of feeble sparks at the spark plug *e* in the engine cylinder as a result of the current induced in the secondary winding *s*. These sparks will be retarded 15 relatively to the stroke of the engine as a result of the inductance of the winding *c* of the buzzer, since the mechanical interrupter is adjusted to a correspondingly advanced position. At the instant of closure 20 of the mechanical interrupter *d* the primary winding *p* is short-circuited and no current traverses the buzzer winding *c*. When the engine has reached sufficient speed, the switch *b* is opened, and the ignition machine 25 *a* operates alone in conjunction with the mechanical interrupter *d* to produce single sparks of the proper character for ignition of the combustible mixture in the engine cylinders. These sparks will be produced 30 at an advanced period relatively to the stroke of the engine since they follow without appreciable delay the period of opening of the mechanical interrupter.

It will be obvious that, if desired, the secondary winding *s* of the ignition machine 35 may be omitted, although the described arrangement is preferable. Furthermore, the system herein shown may be adapted to a multicylinder combustion engine by the 40 addition of a distributor and a plurality of spark plugs according to the ordinary arrangement.

Having thus described my invention, what I claim is:

45 1. In an electrical system for igniting the combustible mixtures during the starting and running of an internal combustion en-

gine, the combination with a spark plug in the engine cylinder of an engine-driven ignition machine connected to supply ignition 50 voltages to said plug, said machine having an inducing winding included in two electrical paths enabling it to produce at said plug retarded and advanced ignition sparks during the starting and running periods respectively, one of the said paths including 55 an engine-driven mechanical interrupter adjusted to effect advanced ignition during running, and the other of said paths including a switch and a buzzer whose winding 60 has electrical inductance such that upon the actuation of said interrupter during the starting period there is produced a retarded succession of sparks at the said spark plug, substantially as described. 65

2. In an electrical ignition system for igniting the combustible mixtures during the starting and running periods of an internal combustion engine, the combination with a spark plug in the engine cylinder of 70 an engine-driven ignition machine provided with a primary and a secondary winding connected in series with the plug, the primary winding being included in two electrical paths, enabling it to induce in the 75 secondary winding voltages capable of producing at said plug retarded and advanced ignition sparks during the starting and running periods respectively, one of said paths including an engine-driven mechanical in- 80 terrupter, adjusted to effect advanced ignition during running, and the other of said paths including a switch and a buzzer whose winding has electrical inductance such that upon the actuation of the said interrupter 85 during the starting period a retarded succession of sparks is produced at the said plug, substantially as described.

In testimony whereof I affix my signature, in presence of two witnesses.

GOTTLOB HONOLD.
